UNITED STATES PATENT OFFICE

HORACE H. RAYMOND, OF BERLIN, CONNECTICUT, ASSIGNOR TO THE STANLEY WORKS,
OF NEW BRITAIN, CONNECTICUT, A CORPORATION OF CONNECTICUT

DESIGN FOR A HINGE LEAF

Application filed April 5, 1930. Serial No. 35,177. Term of patent 14 years.

To all whom it may concern:

Be it known that I, HORACE H. RAYMOND, a citizen of the United States, and a resident of Berlin, in the county of Hartford, State of Connecticut, have invented a new, original, and ornamental Design for a Hinge Leaf, of which the following is a specification, reference being had to the accompanying drawing, forming a part thereof.

Figure 1 is a top plan view of a hinge leaf embodying the new design.

Figure 2 is a side view of the hinge leaf shown in Figure 1, and Figure 3 is a cross section taken about on the plane represented by the line 3—3 of Figure 1.

I claim:

The ornamental design for a hinge leaf, as shown.

HORACE H. RAYMOND.
